UNITED STATES PATENT OFFICE.

JOSEPH E. FALCK, OF PITTSBURGH, PENNSYLVANIA, ASSIGNOR TO NATIONAL CASKET COMPANY, INC., A CORPORATION OF NEW YORK.

DESIGN FOR A BURIAL CASKET.

Application filed April 6, 1928. Serial No. 26,148. Term of patent 14 years.

To all whom it may concern:

Be it known that I, JOSEPH E. FALCK, a citizen of the United States, residing in Pittsburgh, county of Allegheny, and State of Pennsylvania, have invented a new, original, and ornamental Design for Burial Caskets, of which the following is a specification, reference being had to the accompanying drawing, forming a part thereof.

Fig. 1 is a perspective view; and
Fig. 2 is an end view of a burial casket showing my new design.

I claim:

The ornamental design for a burial casket substantially as shown.

JOSEPH E. FALCK.
